UNITED STATES PATENT OFFICE.

WILLIAM T. D. CAMPAIGNE, OF SPOONER, WISCONSIN.

WHEEL-FLANGE OILER.

1,389,420.

Specification of Letters Patent. Patented Aug. 30, 1921.

Application filed October 21, 1919. Serial No. 332,210.

To all whom it may concern:

Be it known that I, WILLIAM T. D. CAMPAIGNE, a citizen of the United States of America, residing at Spooner, in the county 5 of Washburn and State of Wisconsin, have invented new and useful Improvements in Wheel-Flange Oilers, of which the following is a specification.

The object of the invention is to provide 10 an efficient means for supplying oil to the wheel flanges of cars and like vehicles under such conditions as to be operative only when required or when the wheels are in motion, or in other words as applied to railway and 15 similar cars when the engine is in operation or when steam has been used, particularly as devices of this class are generally employed in connection with the flanges of the locomotive wheels, and with this object in 20 view the invention consists in a construction and combination of parts of which a preferred embodiment is shown in the accompanying drawing, wherein:

Figure 1 is a plan view of the apparatus 25 with the oil dispensing nozzles disposed in operative relation with car wheel flanges.

Fig. 2 is an elevational view of the same.

Fig. 3 is a detail sectional view of one of the nozzles.

30 The purpose of the apparatus is to provide for feeding oil, grease or similar suitable lubricant to the wheels under steam pressure only when the steam is turned on for operating the engine of the locomotive, 35 and to this end the feed pipe 10 thereof should be connected by a steam pressure pipe 11, which may have any suitable controlling valve or stop cock 12 with a convenient steam supply pipe 13 into which steam will 40 be turned by opening the throttle of the engine and which of course can be effected in a variety of ways without modifying the operation of this apparatus and hence without necessitating specific illustration in this connection. 45 The feed pipe is arranged terminally in communication with nozzles 14 which are respectively disposed in operative relation with car wheels indicated at 15, a single apparatus ordinarily being employed 50 to supply oil to the transversely opposite wheels of the truck. It is also the purpose to apply the oil to the wheels at the lines of intersection of the treads 16 with the inner surfaces of the flanges 17, or at the angle 55 formed by said tread and flange surfaces, and to do this effectively the nozzles are

arranged in angular positions both with relation to a horizontal and with relation to vertical planes embracing the feed pipe 10. In other words the nozzles incline either forwardly or rearwardly substantially at an angle of 45 degrees to a horizontal plane, and inwardly or toward each other at an angle approximating 45 degrees so that the outlet ends of the reduced nozzle tips 18 60 impinge against the wheels at the line represented by the angle between the tread and flange surfaces of the same and in angular relation with both surfaces. This nozzle tip is mounted for axial movement in the 65 sleeve 19 which is connected as by a threaded joint 20 with the casing 21 of the nozzle, the passage through the tip being reduced to a very small diameter and the inner end of the tip being provided with a follower head 70 75 22 fitted to the bore of the sleeve shown at 23 where it is exposed to pressure in the casing of the nozzle. This tip is free to move relative to the casing and is held extended with its outlet extremity in contact with the 80 wheel at the point indicated by the internal pressure in the casing and yet is free to yield or to be repressed against said pressure by the wheel due to any vibrations of the latter. In other words the tip is yieldingly 85 mounted in the casing so as to compensate for any movements of the car wheel relative thereto while maintaining a contact of its outlet extremity with the wheel.

Within the casing which is attached to 90 the extremity of the feed pipe 10 by a collar 24 is arranged a piston valve 25 in connection with which is arranged a spring 26 adapted to yieldingly hold the valve in position to close a by-pass 27 leading from a steam 95 chamber 28 in direct communication with the feed pipe 10 and the oil chamber represented by the bore 23 of the sleeve 19. Normally the piston valve closes the by-pass to prevent the escape of a lubricant or restrain any internal pressure to avoid the feeding of the oil or other lubricant but as soon as steam or other motive pressure is turned on at the source and is supplied to the feed pipe 10 it acts upon the piston valve to expose 100 the by-pass and thus permit fluid pressure to be applied to the lubricant to discharge the same through the tip of the nozzle. The by-pass is also preferably provided with a needle valve 29 adapted for engagement with 105 a suitable seat 30 and designed to serve as a means of permanently cutting off the sup-

ply of lubricant or of regulating the pressure conveyed by the by-pass and hence that which is applied as a means of expelling the lubricant. It will be noted that in addition 5 to the reduction or throttling action incident to the use of the by-pass and the needle valve there is a reduction as between the oil or lubricant containing chamber of the nozzle and the discharge tip.

10. What is claimed is:

1. A wheel flange oiler having a nozzle provided with an extensible discharge tip having a follower head, a casing with which the discharge tip is removably connected, 15 the said casing being provided with a longitudinal bore, a spring actuated piston valve housed in said bore, the casing being formed with a by-pass communicating with the bore at opposite ends of the piston valve and 20 adapted to be closed at one end by said valve, and means for communicating fluid pressure

to the casing to actuate the valve to open said by-pass as herein shown and specified.

2. A wheel flange oiler having a nozzle provided with an extensible discharge tip 25 having a follower head, a casing with which the discharge tip is removably connected, the said casing being provided with a longitudinal bore, a spring actuated piston valve housed in said bore, the casing being formed 30 with a by-pass communicating with the bore at opposite ends of the piston valve and adapted to be closed at one end by said valve, a needle valve carried by said casing and controlling the said by-pass, and means for communicating fluid pressure to the casing to actuate the valve to open said by-pass as herein shown and specified.

In testimony whereof I affix my signature.

WILLIAM T. D. CAMPAIGNE.
